UNITED STATES PATENT OFFICE.

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

FEEDING MECHANISM FOR REDUCING APPARATUS.

Application filed December 30, 1921. Serial No. 526,024.

To all whom it may concern:

Be it known that I, ALONZO LINTON BAUSMAN, a citizen of the United States, residing at Springfield, in the county of Hampden and State of Massachusetts, have invented new and useful Improvements in Feeding Mechanism for Reducing Apparatus, of which the following is a specification.

This invention relates to reducing apparatus and, more particularly, to the mechanism for feeding materials thereto. The invention is, in some of its aspects, an improvement on that disclosed in my U. S. Letters Patent No. 1,337,584, granted April 15, 1920.

While the invention is capable of other applications it finds one advantageous use as a means for feeding peanuts together with salt to an apparatus by means of which they are reduced to the condition of a paste, forming peanut butter. Obviously, the invention may be used for feeding other nuts, kernels, or materials of generally similar characteristics, and injecting into this material other substances for seasoning, flavoring or otherwise treating the mass.

One object of the invention is to provide, in connection with a suitable reducing apparatus, improved means for feeding material thereto.

Another object of the invention is to provide in connection with a feeding means for one material, an auxiliary means for feeding another material to the first named material to be distributed therein and admixed therewith.

Another object of the invention is to provide a feeding mechanism operable to discharge by gravity flow through a gaged, and preferably regulable outlet, and means for maintaining the material back of the outlet at substantially a constant level, whereby the pressure, a factor contributing to rate of flow, is maintained uniform.

Another object of the invention is to provide a machine for making nut pastes, such as peanut butter, which machine comprises a reducing apparatus, a feeding mechanism for supplying nuts thereto and means for supplying salt to the nuts as they are fed to the reducing apparatus.

Other objects and advantages will appear in the following description and in the illustrative embodiment of the invention in the accompanying drawings, in which,—

Fig. 1 is a side elevational view, with parts broken away, of the complete apparatus;

Fig. 2 is across-sectional view of the supply container, showing part of the elevating means; and

Fig. 3 is an enlarged front elevational view showing the reducing apparatus and feeding means therefor.

Referring to these drawings, the apparatus includes a suitable reducing machine, which by preference is of the same general type as disclosed in U. S. Letters Patent No. 1,098,325, granted May 26, 1914 on an invention of Theodor Kihlgren. That is, the machine involves two disk-like members *a*, which have on their adjacent faces suitable reducing surfaces and are mounted in spaced parallel relation, and an intermediate member *b* carrying on each face a disk *c*, which has reducing surfaces to cooperate with those on disks *a*. Material to be reduced is supplied to the spaces between the cooperating plates *a* and *c* by means of two spaced chutes *d* and means are provided for producing a relative rotary movement between these plates. In this instance, the member *b*, carrying plates *c* is fixed to a shaft *e*, supported in pedestals *f*, and the plates *a* are carried by members *g*, one of which is supported by one pedestal *f* and the other is supported from the first-named member in a suitable manner, which is conventionally indicated in the drawings and more fully exemplified in my prior U. S. Letters Patent No. 1,203,461, granted October 31, 1916.

For supplying material to the chutes *d* of the reducing apparatus, a feeding hopper 5 is provided, which is stationarily supported from and above the reducing apparatus by suitable means, such as those indicated at 6. The lower end of hopper 5, which is open, is received between two spaced upstanding side flanges 7 of a curved directing plate 8, which closes the otherwise open end of the hopper. The side walls of hopper 5 extend into close proximity to plate 8 but the end walls are spaced therefrom, hav-

ing outlet openings 9, which may be gaged or regulated by adjustable gates 10, whereby to vary and control the rate of flow.

The directing device 8 is pivoted at 11 centrally between chutes *d* and is arranged to be rocked or oscillated about this pivot to direct the flow first into one and then into the other chute *d*. To this end, a link 12 connects member 8 to an arm 13 fixed to a 10 rock shaft 14 rotatably supported from one of the chutes *d*. Also fixed to shaft 14 is an arm 15 which is connected by a link 16 to one arm of a bell crank lever 17, pivotally supported by the last-named chute *d*. The 15 other end of lever 17 is connected by a link 18 to a crank pin 19 carried by a gear 20 rotatably supported from the right hand pedestal *f* and driven by a gear 21 on shaft *e* and thus proportionately with the speed 20 of the grinding discs *a* and *c*. The crank pin 19 and lever 17 each have a ball and socket connection with link 18. From the foregoing, it will be seen that on each revolution of shaft *e*, plate 8 will be given one 25 complete oscillation and will first deliver a charge to one chute *d* and then to the other.

In adapting the apparatus for the specific use of making peanut butter, it is necessary 30 to provide means for supplying salt as well as nuts to the reducing apparatus and, preferably, this salt is supplied to the nuts as they pass to the reducing apparatus. For this purpose, I provide a container 22 which 35 may have a graduated transparent portion 23 (Fig. 3) to enable the amount of salt therein to be readily ascertained at any time. This container 22 is supported from hopper 5, as by brackets 24, and its lower end is connected to the hopper by a tube 25 which extends a substantial distance horizontally into the hopper and terminates with a bevelled end diverging downwardly from the vertical. Rotatable in tube 25 is a worm 26, the 40 inner end of which extends slightly beyond the bevelled end of the tube and the outer end of which is journaled in a bearing on the container 22. The latter is filled with dry salt, which is fed by gravity action to 45 worm 26 and the latter, as it turns, feeds the salt into the hopper 5, where it mingles with the nuts flowing therethrough.

The means for turning worm 26 is connected to the mechanism for rocking the 50 directing plate 8, so that, on each oscillation of the latter, the worm is turned to deliver a charge of salt to the nuts in hopper 5. Thus, measured charges of salt are delivered 55 into the hopper on each cycle of the mechanism which delivers nuts to the reducer. To this end, a ratchet 27 is fixed to the outer end of the worm shaft 26' and pivotally mounted intermediate its ends on this shaft between the ratchet and container 22 60 65 is a lever 28, the upper extension of which

carries a pawl 29 to engage the ratchet. The lower extension of lever 28 has a longitudinal slot 30 in which is received a stud 31 carried by one end of a link 32, and this stud may be adjustably secured to the lever in various positions of longitudinal adjustment by a thumb nut 33. The other end of link 32 is pivotally connected to an arm 34 fixed on the shaft 14 already described.

For the purpose of conveniently filling 70 hopper 5 and keeping it filled to the desired level, I provide elevating means which will carry nuts from a relatively large supply container on the floor and deliver them into the hopper. Such container is shown at 75 80 85 and consists of an open top receptacle having an outlet opening 36 in one of its side walls and inclined bottom walls 37 sloping downwardly toward the outlet. Adjacent the container 35 and with its lower end in communication with outlet 36 is an upwardly extending casing 38 which houses the elevator. The latter consists of an endless chain 39 mounted on vertically spaced sprockets 40 fixed to shafts 41 journaled in the side walls of casing 38. A series of buckets 42 are connected to chain 39 at suitable intervals and each is arranged to pick up a charge of nuts from the base of casing 38, carry it upwardly and discharge it into a chute 43 which in turn discharges into hopper 5.

It is important that the rate of flow of 90 nuts to the reducer be maintained as nearly uniform as possible. The rate of flow is controlled by the adjustable gates 10, which 95 control the area of the outlet of hopper 5. The rate of flow is, however, dependent on the pressure back of the outlet as well as the area thereof and it is essential therefore that 100 such pressure be maintained, as nearly as possible, at a uniform figure. To this end, I provide means for maintaining the supply of nuts in hopper 5 substantially at a constant level. This result is accomplished 105 by feeding nuts to hopper 5 at a rate somewhat in excess of that at which they are discharged,—the excess being returned to the container 35. The excess of feed need not be very great and would not be required 110 at all if it were practically feasible to control the elevator feed and hopper feed with in close limits so that each would feed at equal rates. There will, as a practical matter, be some variation and because of this 115 fact and to insure that the level never runs 120 low, I provide for the excess feed. The control of the elevator feed is effected by sliding gates 44 which vary the effective area of outlet 36. The excess of nuts above the desired level in hopper 5 is returned by a 125 chute 45 which connects the hopper to a vertical chute 46 formed in casing 38 and chute 46 terminates in a chute 47 which is directed into container 35 (Fig. 2).

The elevator is driven in the following 130

manner. A pulley 46' fixed on a shaft 47' mounted in casing 38 is connected by a belt 48 to a pulley (not shown) on the shaft *e* of the reducer. Fixed to shaft 47' is a pinion 49 which drives through intermediate gearing 50 a gear 51 fixed on the lower shaft 41.

The operation of the apparatus will sufficiently appear from the foregoing description.

It should be noted that the invention may often times be used without the automatic feed for hopper 5, which, although desirable and preferred, is not indispensable. Also that the salt supplying means may be used in conjunction with any suitable nut feeding means as well as the specific one disclosed. The invention is likewise capable of other applications and is not limited to the one specific use which has been disclosed herein for illustrative purposes. The scope of the invention is defined by the appended claims rather than by the foregoing description.

What I claim is:—

1. In apparatus of the class described, two spaced members having reducing surfaces on their adjacent faces, an element between said members having reducing surfaces on each face to cooperate with the first-named surfaces in reducing material fed therebetween, spaced chutes into which material is supplied and by which it is directed between the cooperating reducing surfaces, a stationary feeding hopper having an outlet gaged to permit discharge of material by gravity at a measured rate of flow, an oscillatory directing device upon which the material from said hopper is received and by which it is directed alternately into said chutes.

2. A machine for making peanut butter and the like, comprising, a reducing apparatus by which the nuts are reduced to the condition of a paste, a passage through which the nuts are fed to the reducing apparatus, a container for salt and the like, a passage connecting the container and the first named passage, a worm rotatable in the last named passage, and pawl and ratchet driving connections between the

worm and reducing apparatus to drive the worm at a speed proportional on the speed of the latter.

3. In combination, a reducing apparatus, a hopper, means for feeding material at a measured rate from the hopper to said apparatus, a supply container for the material, elevating means for carrying material to said hopper at a rate somewhat in excess of that at which it is discharged, and a return connection between the hopper and container through which the excess material above a certain level in the hopper may overflow, whereby a substantially constant level of material is maintained in said hopper.

4. In apparatus of the class described, two spaced members having reducing surfaces on their adjacent faces, an element between said members having reducing surfaces on each face to cooperate with the first-named surfaces in reducing material fed therebetween, spaced chutes into which material is supplied and by which it is directed between the cooperating reducing surfaces, a stationary feeding hopper having an outlet gaged to permit discharge of material by gravity at a measured rate of flow, and an oscillatory directing device upon which the material from said hopper is received and by which it is directed alternately into said chutes.

5. In apparatus of the class described, two spaced members having reducing surfaces on their adjacent faces, an element between said members having reducing surfaces on each face to cooperate with the first-named surfaces in reducing material fed therebetween, spaced chutes into which material is supplied and by which it is directed between the cooperating reducing surfaces, a stationary feeding hopper located above and between said chutes and having an open lower end, a curved trough-like directing device cooperating with said hopper to close said end except for gaged outlets through which material is discharged at a measured rate, and means for oscillating said device so that the material from the hopper is directed first into one and then into the other chute.

In testimony whereof I have affixed my signature.

ALONZO LINTON BAUSMAN.
